UNITED STATES PATENT OFFICE.

PER ALBERT FRESK, OF ROBERTSFORS, SWEDEN.

METHOD OF CHARGING CELLULOSE DIGESTERS AND THE LIKE AND MEANS THEREFOR.

Application filed April 4, 1927, Serial No. 180,987, and in Sweden December 21, 1926.

For the charging of cellulose digesters, the method of causing the charge or the chips to be entrained by a gaseous or vaporous medium forced into the digester has been applied to great advantage. In order then to effect the spreading of the chips uniformly over the whole surface of the digester, it has proved advantageous to impart a rotary movement to the body of chips entrained with the gas or vapor current. To this end, purely mechanical contrivances have been employed heretofore, said contrivances having been devised in such a manner as to be able to catch the chips entrained with the gas or vapor current and to hurl them around and outwards.

According to the present invention, another method is provided, which has proved exceedingly efficient and which has entailed considerable practical advantages. The mechanical means required for the spreading will thus be simplified to a very great extent, and the chips will be very uniformly distributed and will also be tightly packed. The charging takes place, without the chips being impeded by any member in the path thereof, and for this reason there will be no reduction of the rate at which the chips are forced into the digester and, consequently, the tight packing of the chips is furthered in a high degree.

The method according to the invention is principally characterized by the fact that the chips, while being entrained by the medium forced into the digester, are caused to rotate by the medium, the chips being guided during the introduction thereof in such a manner as to be caused to rotate.

The accompanying drawing illustrates an example of charging means suitable for carrying out the method of the present invention.

Fig. 1 shows the apparatus in vertical section on line *a*—*b* in Fig. 2, which latter figure shows the apparatus viewed from above and in horizontal section. Fig. 3 shows a detail to an enlarged scale.

The arrangement illustrated in the drawing is assumed to operate with compressed air forcing the chips into the digester. The compressed air, which is preferably produced by means of a fan (not shown in the drawing), enters through the inlet 1 and flows further inwards through the passage 2. This passage is limited outwards by the spiral-shaped wall 3, and inwardly by the conical filling funnel 4 to the outside of which the wall 3 is connected, as at 5. The compressed

air entering through the inlet 1 will thus follow the wall 3 in its way inwards, and is guided by this wall in such a manner that, when the air penetrates further down through the nozzle 6 which forms an annular opening, the air will have a powerful rotary movement. In passing the nozzle, the air encounters the chips fed down from the funnel 4, a powerful screwing movement being then imparted to the chips under the influence of the air, in a direction downwards through the tube 7. When the chips finally leave the tube, they will be uniformly spread out over the whole surface of the digester by reason of the above mentioned screwing movement. Thus this introduction of the chips will take place practically without any resistance whatever, and the effect with which the chips are packed will thus be correspondingly complete. After the air has performed this work, it returns to the fan through the annular opening 8 and the air distributing chamber 9, through a pipe (not shown) connected to the inlet side of the fan, and will then, as long as the apparatus is in operation, perform the cycle and work described.

The apparatus is adjusted for a greater or smaller passage of air or vapor, i. e. for a more or less intense spreading- and packing action, by the following arrangement. The area of the passage 2, the size of which should be in a certain relation to the area of the annular nozzle 6, is adapted to be controlled by the wall 3 which is adjustable and for this purpose provided with fittings 10 cooperating with fixed fittings 11. Both kinds of fittings are provided with elongated slots 12 and 13 respectively having screws 14 extending therethrough. By loosening the screws, the fittings may be displaced relatively one another, according to the desired adjustment of the wall, and the adjustment is secured by screwing up the screws. For this purpose, the spiral-shaped wall 3 may, without being subjected to any alterations of its shape, be movable horizontally to and fro in all directions. The funnel 4 is adapted to be raised and lowered within wide limits and is, if desired, adjustable laterally, in order to be able to increase or decrease the area of the annular nozzle 6, or, perhaps, to give the funnel an eccentric position with respect to the tube 7. To this end, the funnel is carried by fittings 15 (see Fig. 3) cooperating with screws 16 and 17, the first mentioned of which extend through elongated slots 18 in the wall of the funnel 4,

while the latter screws likewise extend through elongated slots 19 in the fixed wall 20.

What I claim is:—

1. An apparatus for charging cellulose digesters comprising a feeding funnel through which the charge is introduced, a gas conveying passage through which a gaseous medium is forced into the digester, said passage extending helically around said funnel, 5
10 said helical passage opening into the space adjacent the outlet opening of the funnel whereby the charge when leaving the outlet opening of the funnel is caught by the gaseous medium and is entrained in the movement 15 thereof.

2. An apparatus according to claim 1 in which the gas conveying passage is formed of a spiral wall surrounding said feeding funnel, a wall connecting said spiral wall to 20 the outside of the wall of the funnel, a downwardly extending annular funnel-shaped member secured to the spiral wall extending below the lower end of said feeding funnel and forming an annular space between said 25 funnel members.

3. An apparatus according to claim 1 in which the gas conveying passage is formed of a spiral wall surrounding said feeding funnel, a wall connecting said spiral wall to 30 the outside of the wall of the funnel, a downwardly extending annular funnel-shaped member secured to the spiral wall extending below the lower end of said feeding funnel and forming an annular space between said 35 funnel members and means to adjust the spiral wall horizontally to vary its relation to the feeding funnel.

4. An apparatus according to claim 1 in

which the gas conveying passage is formed of a spiral wall surrounding said feeding 40 funnel, a wall connecting said spiral wall to the outside of the wall of the funnel, a downwardly extending annular funnel-shaped member secured to the spiral wall extending below the lower end of said feeding funnel 45 and forming an annular space between said funnel members and means to adjust the feeding funnel vertically with relation to the spiral wall.

5. An apparatus according to claim 1 in 50 which the gas conveying passage is formed of a spiral wall surrounding said feeding funnel, a wall connecting said spiral wall to the outside of the wall of the funnel, a downwardly extending annular funnel-shaped member secured to the spiral wall extending below the lower end of said feeding funnel and forming an annular space between said funnel members, means to adjust the spiral wall horizontally to vary its relation to the feeding funnel 55 and means to adjust the feeding funnel vertically with relation to the spiral wall. 60

6. An apparatus according to claim 1 in 65 which the gas conveying passage is formed of a spiral wall surrounding said feeding funnel, a wall connecting said spiral wall to the outside of the wall of the funnel, a downwardly extending annular funnel-shaped member secured to the spiral wall extending below the lower end of said feeding funnel 70 and forming an annular space between said funnel members, and means to adjust both the feeding funnel and the spiral wall relative to each other. 75

In testimony whereof I affix my signature.
PER ALBERT FRESK.
